UNITED STATES PATENT OFFICE.

ARTHUR J. FARMER, OF DETROIT, MICHIGAN.

MEANS FOR EXTRACTING THE CONTENTS OF BOTTLES.

No. 922,758.

Specification of Letters Patent.

Patented May 25, 1909.

Application filed November 7, 1907. Serial No. 401,138.

To all whom it may concern:

Be it known that I, ARTHUR J. FARMER, citizen of the United States, residing at Detroit, county of Wayne, State of Michigan, have invented a certain new and useful Improvement in Means for Extracting the Contents of Bottles, and declare the following to be a full, clear, and exact description of the same, such as will enable others skilled in the art to which it pertains to make and use the same, reference being had to the accompanying drawings, which form a part of this specification.

My invention relates to an improvement in toilet articles, and more particularly foun-
15 tain combs, the object being to construct a device capable of extracting the fluid con-
tents of a bottle or other container, being also
adapted to apply said liquid directly to the
scalp without danger of soiling the hands.

A further object is to provide a device that
can be charged only from a container espe-
cially designed for use in connection therewith and which is the subject matter of a
20 separate application for patent.

Referring to the drawings forming part of
this specification: Figure 1 is an elevation of
a collapsible bulb engaging the nozzle portion
30 of the comb, with parts broken away
and in section to more clearly disclose the
construction. Fig. 2 is an elevation, with
parts in section, of the comb proper showing
it disconnected from the nozzle portion.
Fig. 3 is a sectional view of a detail showing
35 the manner of engaging the guard or guide
rod to the nipple on which the bulb is
mounted. Fig. 4 is a cross-sectional view
on line $x-x$ of Fig. 3. Fig. 5 is a view of the
container showing in dotted lines the bulb
40 with its nozzle inserted in the bottle in position
to extract the contents thereof.

Referring to the letters of reference shown
on the drawings: A indicates a comb having
a hollow back A', in which are set tubular
45 teeth A² communicating therewith.

B is a nozzle screw-threaded at its end to
engage the screw-threaded end of the tubular
back A'. B' is a drip cup surrounding the
nozzle, and B² is a nipple on which is mount-
50 ed the collapsible bulb C.

D is a guard and guide rod, soldered or
otherwise secured at d to the nipple and ex-
tending through the opening in the nipple
and that of the nozzle to the extreme end of
55 the hollow back of the comb when the parts
are assembled. The rod is flattened on one

side as indicated in Fig. 4 to increase the open area surrounding it at the nozzle and nipple.

Referring now to the container previously 60 mentioned: E is a bottle in which is housed a tube F extending its entire length being supported at one end in the neck of the bottle by the cork G. H is a wax seal over the cork and I is an air vent tube projecting 65 through the cork and seal. J is a rubber nipple fitted over the end of the tube, its end projecting above the cork and seal.

The rod D attached to the bulb portion of the comb serves a double purpose as will now 70 be explained.

When it is desired to extract the contents of the bottle E the bulb portion is separated from the comb proper by unscrewing the nozzle B attached to the comb back A'. 75 The rod D is then inserted in the nipple J and tube F and serves to guide the nozzle B into the end of the nipple J which being formed of rubber closes tightly around the nipple making an air tight seal therewith. 80 The bulb C (previously collapsed) is now permitted to assume its normal shape, which action serves to suck into the bulb a portion of the contents of the bottle;—the bulb portion is then disconnected from the nipple 85 and attached to the comb proper by which means the liquid is applied to the scalp by compressing the bulb as required. Attention is now called to the fact that the rod D serves also as a guard to prevent the bulb 90 being charged with a fluid not housed within an especially designed container, as the projecting rod would interfere with attempts to immerse the end of the nozzle in a fluid not contained in a bottle especially constructed to serve in conjunction with the instrument described.

Having thus described my invention, what I claim is:

1. In an instrument for extracting the 100 fluid contents of a bottle, a collapsible bulb portion, a nozzle connected with the bulb portion, and a guard and guide rod connected to the nozzle and projecting a relatively long distance beyond the outer end of the nozzle 105 for the purpose specified.

2. In an instrument of the character de-
scribed, a tubular member, a nozzle de-
tachably secured to the tubular member, a
bulb detachably secured to the nozzle, and a 110 guide and guard rod projecting through the
nozzle and into the tubular member when

- the parts are assembled, said rod having one side flattened to increase the area of space between it and the nozzle.
3. In an instrument of the character described, a bulb, a nozzle, a drip cup carried by the nozzle, and a guide and guard rod extended through the nozzle and projecting beyond the outer end thereof, one side of the rod being flattened to increase the area of space between the rod and the nozzle at opposite ends of the latter.
4. In an instrument for extracting the contents of a bottle, a collapsible bulb portion, and a guard and guide element projecting a relatively long distance beyond the outer end of the nozzle, said rod having one side flattened to increase the area of space between the rod and the nozzle at opposite ends of the latter.
5. An instrument of the character described comprising a nozzle, a bulb connected to the nozzle, and a combined guard and guide rod passed through the bore of the nozzle and projecting a relatively long distance beyond the outer end of the nozzle.
6. An instrument of the character described comprising a nozzle, a bulb connected to the nozzle, and a combined guard and guide rod passed through the bore of the

nozzle and projecting a relatively long distance beyond the outer end of the nozzle, one side of the rod being flattened to increase the area of space between the rod and nozzle.

7. An instrument of the class described comprising a nozzle, a bulb connected to the nozzle, a drip cup on the nozzle, and a combined guard and guide rod passed through the nozzle with its inner end secured to the inner end of the nozzle and at its outer end projecting a relatively long distance beyond the outer end of the nozzle.

8. An instrument of the class described comprising a nozzle, a bulb connected to the nozzle, and a combined guard and guide rod passed through the nozzle with its inner end bent and secured to the inner end of the nozzle and at its outer end projecting a relatively long distance beyond the outer end of the nozzle, one side of the rod being flattened to increase the area of space between the rod and nozzle.

In testimony whereof, I sign this specification in the presence of two witnesses.

ARTHUR J. FARMER.
